UNITED STATES PATENT OFFICE.

JOHN A. MAKER, OF DULUTH, MINNESOTA.

DISK-HOLDER.

1,130,914.

Specification of Letters Patent.

Patented Mar. 9, 1915.

Application filed April 28, 1914. Serial No. 834,924.

To all whom it may concern:

Be it known that I, JOHN A. MAKER, a citizen of the United States, residing at Duluth, in the county of St. Louis and State of Minnesota, have invented certain new and useful Improvements in Disk-Holders, of which the following is a specification.

My invention relates to disk holders of the type employed in connection with abrasive disks of small size, such for instance, as are used by dentists, my more particular purpose being to provide an efficient mounting for the disk while the latter is subjected to rapid rotation.

My invention is particularly adapted for use in connection with dental engines, and provides means by which abrading disks, provided with or carrying emery, garnet, sandpaper, cuttlefish bone, crocus, carborundum, or any similar substance, may be readily mounted upon and easily detached from a rotary spindle.

By my invention, a disk of the kind just mentioned may be readily and conveniently mounted in position, and one may be easily and quickly interchanged for another.

I further seek to produce a device of the character under discussion so arranged that the disk is firmly held in position upon the spindle until released by pressure applied for the purpose upon a release spring, and so that any unusual pressure brought to bear upon the disk while in use, as is often necessary where the abrasive material carried by the disk consists of coarse grit, the disk cannot be pried loose.

It is a custom among dentists to avoid rotating a disk or stone so that the travel of the abrasive surface thereof is toward the gum of the patient. That is to say, the abrasive must follow the grain rather than go against the grain. My device therefore, is well adapted for avoiding the difficulty of working against the grain of the gum.

Reference is made to the accompanying drawings forming a part of this specification, and in which like letters indicate like parts.

Figure 1 is a side elevation of a mandrel stem or drill shank, equipped with one form of my invention. Fig. 2 is a vertical section through the same. Fig. 3 is an end elevation of the mandrel stem, the disk and fastenings therefor being removed. Fig. 4 is a detail view, showing in perspective the latch forming part of the fastening mechanism.

Fig. 5 is a section somewhat similar to Fig. 2, but showing a different form of the fastening mechanism and a different type of disk secured thereby. Fig. 6 is an end elevation of the mandrel stem shown in Fig. 5, the disk and fastening therefor being removed. Fig. 7 is a fragmentary plan, showing still another type of disk, and parts carried by the same.

A mandrel stem appears at 8, and is provided with an enlarged portion 9, and with a head 10 of substantially frusto-conical form, these parts, in this instance, being integral. The head 10 carries three small lugs 11, each having the proximate form of a steep pyramid. The enlarged portion 9 is provided with a hole 12, the latter being flared slightly at 13. A cap 14 is provided centrally with a stem 15, the latter having a reduced portion 16 and a shoulder 18. One end of the stem 15 is provided with a dull point 17 to facilitate its entering the hole 12.

A leaf spring 19 is mounted upon the enlarged portion 9 of the mandrel stem, and is held in position by a rivet 19a. The spring 19 carries a bent portion 20 having the proximate form of a stirrup and provided with a cross portion 21 which is nearly straight. This portion fits into a slot 21a with which the enlarged portion 9 of the mandrel stem is provided.

An abrasive disk is shown at 8a. In order to mount the disk in position, the stem 15 is thrust through a hole in the center of the disk and inserted in the hole 12. Pressure now being applied to the cap 14, the lugs 11 are thrust through the disk. The straight portion 21 of the latch now lodges against the shoulder 18, so as to prevent the withdrawal of the stem 15 from the hole 12.

In the form shown in Figs. 5 and 6, the enlarged portion 9 is provided with a head 22 of substantially frusto-conical form, this head carrying a boss 23 having a substantially triangular form in cross section. The enlarged portion 9 is provided with a hole 24. A disk 25, which may be of carborundum or other hard substance, is provided with an opening mating the form of the boss 23. In some instances I may use a disk 26 having a metallic center 27, the latter being provided with a triangular opening 28. By this arrangement undue strain upon the abrasive material of the disk 26 is avoided. The opening 28 simply fits over

the triangular boss 23. A pin 30, provided with a head 29, extends into the hole 24 and is secured by the latch, as above described with reference to Figs. 1 and 2.

- 5 The operation of my device will be readily understood from the foregoing description. The disk or its equivalent being mounted upon the mandrel stem, as illustrated and described, the stem is mounted in 10 a dental engine, or at least connected with a flexible shaft, and is caused to rotate. The disk is then applied to a tooth, a section of bridge work, or other analogous object, and is directed by hand.
- 15 I do not limit myself to the precise construction shown, as variations may be made therein without departing from the spirit of my invention. Neither do I limit myself to the use of disks made of any particular 20 material.

Having thus described my invention, what I claim as new and desire to secure by Letters Patent is as follows:

1. In a disk holder, the combination of a 25 mandrel stem provided with an axially disposed opening and a transverse slot crossing said opening and merging therein, a spring latch mounted on the mandrel stem, and provided with a portion extending into 30 said slot and partially into the axial opening, and a cap for engaging a disk said cap provided with a pin, said pin having a reduced portion adapted to be engaged by the latch when inserted in the axial opening.
- 35 2. In a disk holder, the combination of a mandrel stem provided with an axially disposed opening and with a slot crossing said opening and merging therein, a spring latch mounted upon said mandrel stem and pro-

vided with a portion extending through said 40 slot and partially into said opening, a disk engaging said mandrel stem, and a fastening member engaging said disk and provided with a pin having a shoulder, said pin extending into said opening so that said shoulder 45 engages said portion of said latch.

3. In a disk holder the combination of a mandrel provided with an axially disposed opening and a transverse slot crossing said opening and merging therein, a spring latch 50 mounted on said mandrel stem and provided with a portion extending through said slot and partially into the axial opening, a disk engaging said mandrel stem and a fastening member engaging said disk and provided 55 with a pin, said pin provided with means for engagement by the latch when the pin is inserted in the axial opening.

4. In a disk holder the combination of a mandrel stem having an axially disposed 60 opening and with a transverse slot crossing said opening and merging therein, a spring latch mounted upon said stem and provided with a transversely bent portion having a central opening and extending through said 65 slot and partially into the axial opening, and a fastening member engaging said disk and provided with a pin having a portion of its shank reduced and adapted to be engaged by the transverse portion of the spring latch. 70

In testimony whereof I have signed my name to this specification in the presence of two subscribing witnesses.

JOHN A. MAKER.
